(57) **CLAIM**

The ornamental design for a body piercing instrument, as shown and described.

DESCRIPTION

FIG. 1 is a perspective view of a body piercing instrument, showing the new design;

FIG. 2 is a rear lower perspective view thereof;

FIG. 3 is a front elevation view thereof, where the rear elevation view is a mirror image of the front elevation view;

FIG. 4 is a right elevation view thereof;

FIG. 5 is a rear elevation view thereof, where the front elevation view is a mirror image of the rear elevation view;

FIG. 6 is a left elevation view thereof;

FIG. 7 is a top plan view thereof; and,

FIG. 8 is a bottom plan view thereof.

1 Claim, 6 Drawing Sheets(56)
